UNITED STATES PATENT OFFICE

2,591,756

PENCIL SHARPENER

Glen E. Wimmer, Chicago, Ill.

Application January 26, 1948, Serial No. 4,267

5 Claims. (Cl. 120—96)

1

My invention relates to an improvement in pencil sharpening devices. One purpose is to provide an improved cutter for pencil sharpeners.

Another purpose is to provide an improved frame or support for the cutters.

Another purpose is to provide an improved method of making cutters for pencil sharpeners and for other uses.

Other purposes will appear from time to time in the course of the specification and claims.

I illustrate my invention more or less diagrammatically in the accompanying drawings wherein:

Figure 1 is an end elevation;

Figure 2 is a section on the line 2—2 of Figure 1;

Figure 3 is a section on the line 3—3 of Figure 2;

Figure 4 is an elevation of the cutter support shown in Figure 2;

Figure 5 is a plan view of the structure shown in Figure 4;

Figure 6 is a section, on an enlarged scale, on the line 6—6 of Figure 5;

Figure 7 is a section on the line 7—7 of Figure 6;

Figure 8 is a side elevation, on an enlarged scale, of one of the cutters;

Figure 9 is a section on the line 9—9 of Figure 8;

Figure 10 is a section on the line 10—10 of Figure 9;

Figure 11 is a side elevation of a different form of cutter;

Figure 12 is a section, on an enlarged scale, of another form of cutter;

Figure 13 is an illustration of a variant form of roller support;

Figure 14 is a section on the line 14—14 of Figure 13;

Figure 15 is a section, on an enlarged scale, on the line 15—15 of Figure 13;

Figure 16 is a side elevation, on an enlarged scale, of another form of cutter support;

Figure 17 is a plan view of Figure 16;

Figure 18 is an end elevation of Figure 17;

Figure 19 is a section on the line 19—19 of Figure 17; and

Figure 20 is a view of a variant form.

Like parts are indicated by like symbols throughout the specification and drawings.

Referring to the drawings, I generally indicate any suitable base which may be mounted on or secured to any suitable support, such as the top of a table or desk. It may advantageously be made of a stamping of sheet metal. Upwardly extending from it I illustrate a pedestal 2, shown as formed of sheet metal, and having an integral upper expansion or hub, generally indicated as 3, and having a circumferential flange 4 with circumferentially spaced notches or gaps 5. Mount-

2

ed to be secured to the hub 3 I illustrate a housing shown as formed of two parts, 6 and 7, secured to each other as by opposed flanges 8. In general alignment with the center of the hub 3, the part 7 is shown as having a tubular inward extension 9 which serves as a centering member or support for the below described cutter holding rotor. The member 3 is provided with prongs 10 for interfitting with the notches in the shell member 6, whereby the composite housing member formed of the parts 6 and 7 can be applied to and locked in relation to the offset hub 3. The hub 3, and its flattened part 4, receive an internal gear plate or ring 12 which may be held in place by offset lugs or parts 13 of the hub portion 4.

The rotor for rotating the below described cutters includes a pin or shaft 14 having an enlargement 15 and a reduced handle-receiving end portion 16. The portion 14 is surrounded by a bearing sleeve 17 secured to the hub portion 3 with a press fit, as at 18. The handle 19 serves to rotate the shaft 14 within the bearing sleeve 17 and thus to rotate the yoke portion shown as including two pieces of metal or suitable material 20, 21 positioned back to back, as shown in Figure 5, and having outwardly extending end lugs 22 at one end and 23 at the other.

The parts 20 and 21 can be riveted together, or otherwise suitably secured. Each of the pieces 20, 21 has a pencil receiving opening 24 with an end enlargement 25. Each pair of lugs 22, 23 is apertured, as at 26, to receive the ends of bearing pins 27 which may be suitably headed, as at 28. The yoke structure, which includes the parts 20 and 21, is shown as secured to the shaft enlargement 15 as follows: The lugs 23 are formed with circular, inner, cut-away edges 23a which seat in a circumferential recess or slot 15a in the enlargement 15. The members 20 and 21 have central locking lugs 30 which enter a transverse, diametrically extending slot 31 in the end of the enlargement 15. When the parts are interfitted in the position in which they are shown in Figures 6 and 7, the members 20 and 21 may then be bolted, welded or otherwise secured together. The result is a unitary structure which may be rotated by rotation of the crank 19 and the terminal handle 19a.

Mounted for rotation on the bearing pins 27 are cutters, each of which includes a hollow sleeve or tube 35. Mounted on each such tube are a plurality of disks 36 which may be stamped or otherwise formed, for example, from sheet metal. Each such disk has appropriate teeth 37. A separate disk or member 38 may be employed at one end, having gear teeth 39. It is preferably spaced from the sequence of cutter disks by an intermediate spacer 40 of somewhat smaller diameter. The tube 35 may be headed at each end, as at 41, 42. The disks may be arranged on the tube 35

with the teeth 37 arranged in any suitable pattern. It may, for example, be advantageous to spiral them, as shown in Figure 8. The disk 36 may be locked in position, by press-fitting or otherwise. It will be understood that a variety of manufacturing methods may be employed. For example, the hollow tube 35 may be initially headed or offset at one end, as at 41. The disks 36, the spacer 40, and the pinion disk 38 may be aligned on the tube 35, and, thereafter, the tube may be headed as at 42; or the tube may be outwardly expanded by any suitable tool, in order to insure a press-fit when the parts are properly arranged. It will be understood that any other suitable aligning and positioning means, not herein shown, may be employed.

When the parts are assembled, the pinion teeth 39 mesh with the internal teeth of the gear ring 12. Thus the result of a rotation of the crank 19 is to move the rollers about the end of a pencil inserted through the sleeve 9 and into the space indicated at 24 in Figure 4. At the same time, there is a positive rotation of the two cutters, whereby the pencil is sharpened.

With reference to the form of Figure 12, I illustrate a variant arrangement of cutter teeth. The tube 35 is employed, and headed at each end, as at 41 and 42, but the individual cutter disks 50 have teeth 51 with oppositely extending cutting edges 52. Thus a reversible cutter is provided. It will be understood that the teeth may be spiraled, as shown in Figure 8, or otherwise arranged. In Figure 11, I illustrate them as out of spiral arrangement.

Referring to the form of Figures 13, 14 and 15, I illustrate a variant type of cutter supporting yoke. The shaft 55, with its enlargement 56, receives an end plate or disk 57, which may be press-fitted on or otherwise secured to the central projection 56a. Extending from the end plate, and lying in a plane perpendicular to it, is an intermediate plate 58 having lugs 59 at one end and 60 at the other. The lugs 59 extend through suitable apertures in the disk 57 and are suitably upset or otherwise secured. The plate also has a small key 61 extending into a suitable slot 62 in the enlargement 56a. At the opposite end or edge of the plate 58 is a bearing sleeve 63 which may be press-fitted or otherwise secured in or to the yoke 64, having side arms 65 provided with suitable bearing pin receiving apertures 66. The arms 65 are inclined, just as are the arms 22 of the form of Figure 5, whereby the axes of the bearing pins, not actually shown in Figure 13, are inclined apart at the proper angle to provide the desired cutting cone or formation for cutting or sharpening the end of a pencil. The plate 58 is recessed, as at 58a, to receive the end of the pencil extending through the sleeve 63.

It will be understood that the yoke of Figure 14 may be used with the housing shown in Figure 2, in which case the bearing sleeve 63 extends either into or in alignment with the tube 9. It will be understood, also, that the tube 9 may be omitted, leaving simply an aperture. In that event the sleeve 63 may extend through such aperture. It will be understood that the disk 57 may be bent to align its apertures 57a with the apertures 66 of the end yoke.

Figures 16 to 19, inclusive, illustrate a variant form of yoke, which may be formed or struck out of a single piece. It includes a body portion 75, having outwardly struck, offset yoke arms 76 perforated as at 77 to receive suitable bearing

pins. The body 75 is cut away, as at 78, to receive the pencil end. At the opposite end, the member 75 has shorter yoke arms 79, each with an aperture 80 for a bearing pin, not shown. The yoke thus formed may be suitably secured to the enlargement 82 of the shaft 81. It may, for example, be soldered.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

For example, in Figure 20, I illustrate a variant form in which, instead of the hollow tubular core 35, as shown, for example, in Figure 9, I employ a solid core 100 on which the individual disks 36a are mounted. The individual disks are press-fitted on the core 100.

I claim:

1. In a pencil sharpener which includes a base, a support extending upwardly from said base and a housing removably mounted on the support, a rotor pivoted on said base, said rotor including a shaft portion pivoted on said support and a handle at one end thereof, and a pair of roller receiving yokes secured back to back to each other and secured to the end of said shaft portion opposite to said handle.

2. The structure of claim 1 characterized in that the shaft portion is notched to receive adjacent ends of the roller receiving yokes.

3. The structure of claim 1 characterized in that the roller receiving yokes are of sheet metal and have axially extending plane portions secured to each other.

4. The structure of claim 1 characterized in that the roller receiving yokes have axially extending recesses formed and adapted to receive the end of a pencil, the yokes being secured to each other along opposite sides of said recesses.

5. The structure of claim 1 characterized in that the roller receiving yokes have axially extending recesses formed and adapted to receive the end of a pencil, the yokes being secured to each other along opposite sides of said recesses, the housing having a pencil guiding sleeve aligned with said recesses.

GLEN E. WIMMER.
